[57] **CLAIM**

The ornamental design for transparent patient enclosure for use with respiratory filter apparatus, as shown and described.

DESCRIPTION

FIG. 1 is a perspective view from above of the transparent patient enclosure of the invention;

FIG. 2 is a top plan view of the transparent patient enclosure of FIG. 1;

FIG. 3 is a bottom plan view of the transparent patient enclosure of FIG. 1;

FIG. 4 is a side elevational view of the transparent patient enclosure of FIG. 1, the other side being the same;

FIG. 5 is a front plan view of the transparent patient enclosure of FIG. 1;

FIG. 6 is an end plan view of the transparent patient enclosure of FIG. 1; and,

FIG. 7 is a side view of the other side of the transparent patient enclosure of the invention. The broken line showing of the support brackets, patient and face cone are included for the purpose of illustration only and form no part of the claimed invention.

FIG. I

FIG. 2

FIG. 3

FIG. 4

FIG. 6

FIG. 5

FIG. 7
